[57] CLAIM

The ornamental design for a string fixing device, as shown and described.

DESCRIPTION

FIG. 1 is a perspective view of a string fixing device showing my new design;

FIG. 2 is a front view thereof, the rear view being a mirror image of the front view;

FIG. 3 is a top plan view thereof, the bottom plan view being identical to the top plan view;

FIG. 4 is a right side view thereof, the left side view being a mirror image of the right side view;

FIG. 5 is a front view of the string fixing device, in the condition that a male member thereof is elastically pressed into a female member thereof to align holes respectively provided in the male member and the female member;

FIG. 6 is a top plan view of FIG. 5;

FIG. 7 is a cross sectional view taken along line 7—7 in FIG. 2;

FIG. 8 is a cross sectional view taken along line 8—8 in FIG. 3; and,

FIG. 9 is a cross sectional view taken along line 9—9 in FIG. 2.
